Int. Cl. D12—11

U.S. Cl. D12—213

FIG. 1.

FIG. 2.

FIG. 3.

FIG. 1 is an isometric view of a bicycle wheel ornament showing our new design;

FIG. 2 is a side elevational view thereof; and

FIG. 3 is an end elevational view thereof.

The undisclosed side is a mirror image of the side shown except that the protuberances on the two sides are offset with respect to one another as best illustrated in FIG. 3.

We claim:

The ornamental design for a bicycle wheel ornament, substantially as shown and described.
